(57) **CLAIM**

The ornamental design for a rope cleat for supporting a rope, as shown and described.

DESCRIPTION

FIG. 1 is a front perspective view of a rope cleat for supporting a rope showing the claimed design; FIG. 2 is a front view thereof; and,

FIG. 3 is a side view thereof.

The dashed broken lines in the figures show portions of the rope cleat for supporting a rope and environment that form no part of the claimed design.

The dot-dash broken lines in the figures and the areas within show portions of the rope cleat for supporting a rope that form no part of the claimed design.
